EYE SHADE

James Allan Clark, Coral Gables, Fla.

Application March 31, 1955, Serial No. 35,292

Term of patent 14 years

(Cl. D57—1)

Fig. 1

Fig. 2

Fig. 1 is a top plan view of an eye shade showing my new design.

Fig. 2 is a front elevation of the eye shade shown in Fig. 1.

Fig. 3 is a side view of the eye shade shown in Figs. 1 and 2 with the temples extended.

The end not shown is the same as the end shown.

I claim:

The ornamental design for an eye shade, substantially as shown and described.
